CLAIM

The ornamental design for a bag, as shown and described.

DESCRIPTION

The patent file contains at least one drawing executed in color. Copies of this patent with color drawing(s) will be provided by the Patent and Trademark Office upon request and payment of the necessary fee.

FIG. 1 is a front perspective view of a bag showing my new design;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof;

FIG. 8 is a front perspective view of the design in a second embodiment;

FIG. 9 is a front view of the embodiment of FIG. 8;

FIG. 10 is a back view of the embodiment of FIG. 8;

FIG. 11 is a left side view of the embodiment of FIG. 8;

FIG. 12 is a right side view of the embodiment of FIG. 8;

FIG. 13 is a top view of the embodiment of FIG. 8;

FIG. 14 is a bottom view of the embodiment of FIG. 8;

FIG. 15 is a front perspective view of the design in a third embodiment;

FIG. 16 is a front view of the embodiment of FIG. 15;

FIG. 17 is a back view of the embodiment of FIG. 15;

FIG. 18 is a left side view of the embodiment of FIG. 15;

FIG. 19 is a right side view of the embodiment of FIG. 15;

FIG. 20 is a top view of the embodiment of FIG. 15; and,

FIG. 21 is a bottom view of the embodiment of FIG. 15.
